UNITED STATES PATENT OFFICE.

PERSIFOR FRAZER SMITH, JR., OF PAOLI, PENNSYLVANIA, ASSIGNOR TO THE UNION SWITCH & SIGNAL COMPANY, OF SWISSVALE, PENNSYLVANIA, A CORPORATION OF PENNSYLVANIA.

TRAIN-STOP SYSTEM.

Application filed October 26, 1927. Serial No. 228,901.

This invention relates to train stop systems of the continuous inductive type, in which a plurality of cab indications are given both the engineman and the fireman, inductively, from the rail current, together with means carried on the locomotive for displaying the proper signals, depending upon the track conditions in advance of the locomotive.

10 Another object of this invention is to provide a practical electrical interlocking means through which the primary object of the train stop device cannot be set aside and ignored by the engineman in the operation of the locomotive.

A further object is, to provide means for locking the reset switch through the medium of the double-heading cock.

20 A still further object is to provide an electro-pneumatic switch wherein an electric circuit is broken in the reset switch when the double heading cock is closed.

25 With these and other objects in view, which will be more readily apparent as the nature of the invention is better understood, the same consists in the novel construction, combination and arrangement of parts as will be hereinafter more fully pointed out, illustrated and claimed.

30 It will be readily understood by those skilled in the art to which this invention belongs, that the same is susceptible to some structural changes and modifications without departing from the spirit or scope of the invention, but a preferred and practical embodiment of the invention is shown in the accompanying drawings in which:-

Figure 1 shows a plan view of my improved reset switch, together with a sectional view of the diaphragm and locking plunger used to rotate the shaft of the switch.

Figure 2 shows a sectional view taken on the line 2—2 of Fig. 1 and shows the manner of completing the circuit through the switch.

Figure 3 shows the position of the pneumatically-operated plunger when the switch is in the closed position.

Figure 4 shows the position of the pneumatically-operated plunger when the switch is in its open position.

Figure 5 shows the front and edge views of a ring adapted to be secured to the switch shaft and used when the circuit is opened

and closed, as clearly illustrated in Fig. 2 of the drawings.

Figure 6 shows a front and side elevational view of the ring housing, which is designed to encase the ring shown in Fig. 5.

Figure 7 shows a sectional view taken on the line A—B in Fig. 6 of the drawings.

Figure 7a shows a sectional view taken on the line C—D of Fig. 6 of the drawings.

Figure 8 shows a plan and elevational view of the switch actuating end of the pneumatically-operated plunger, as illustrated in operative position in Fig. 1 of the drawings.

Figure 9 shows a partial sectional view of the double-heading cock that I use in connection with this invention.

Figure 10 shows a sectional view taken on the line 10—10 of Fig. 9, and shows the location of the ports in the plug valve, as well as the position of the ports in the valve casting.

Figure 11 shows a sectional view taken on the line 10—10 of Fig. 9, and shows the plug valve rotated 90 degrees from that shown in Fig. 10 of the drawings.

Figure 12 shows a portion of a side elevation of my improved plug valve used in connection with the double-heading cock.

Figure 13 is an end elevation of the plug valve shown in Fig. 12.

Figure 14 shows an edge and side view of one of the locking bars which engages the bridging element when the switch is in its open position.

Figure 15 shows a sectional view of the engineer's brake valve, with the associated parts used therewith.

Similar reference numerals refer to similar parts throughout the several figures of the drawings.

In carrying out this invention I use a new design of double-heading cock, which is designated in its entirety by the numeral 10 and consists essentially of a body portion 11, in which is positioned a bushing 12. The bushing 12 is provided with a tapered bore into which a plug valve 13 is positioned and adapted to rotate. Cored passages are provided in the bushing and through the plug valve which communicate with inlet and outlet pipes in the body portion 11 of the double-heading cock; as will be pointed out fully in the specification.

In addition to providing a new design of double-heading cock, 10, I provide a new design of reset switch, designated in its entirety by the numeral 14, and consists primarily of a casing 15 through which passes a shaft 16, having a handle 17, attached to one end thereof for the purpose of rotating the shaft. The shaft 16 is further provided with a plurality of current-carrying contact bars 18 and 68, which serve to make and break the circuit at the contact points 19 and 20, as shown in Figure 1 of the drawings.

The reset switch 14 is further provided with an air-operated plunger 21, actuated through the medium of a diaphragm 22, positioned in a casing 23, and adapted to be sandwiched between the flanges 24 and 25, made as an integral part of the base and cap, respectively, of the casing. The diaphragm 22 is provided with a perforation 26 through which one end of the plunger 21 is adapted to pass, while the protruding end 27 is provided with means for holding the plunger securely attached to the diaphragm, as clearly illustrated in Fig. 1 of the drawings.

The case 15 of the reset switch is provided with means for attaching a flange 28, constructed as an integral part of the diaphragm casing 23. The base of the case 23 is further provided with annular recess 29, against which is positioned a spring 30, the free end of which rests against a plate 31, which is sandwiched between the shoulder 32 on the plunger 21 and the diaphragm 22. This resilient element serves to retract the plunger 21 from the break to the make positions of the switch, as shown in Figs. 4 and 3 of the drawings, respectively.

Let us now assume that an engineman has a clear cab signal and is proceeding at the authorized speed, and the cab signals change to the approach restricting position, denoting a change in the track conditions in advance of the locomotive. A warning whistle 32 is sounded, but the engineman fails to acknowledge this change in signals and the brakes are applied. Under normal operation the train would come to a stop and the engineman would be obliged to get off the locomotive and go to the reset switch, and reset, after which the brakes could be released.

Let us further assume that the engineman tries to get the brakes released without bringing the locomotive to a stop as required and proceeds by closing the double-heading cock in which case air from pipe 34, of the application control valve, designated in its entirety by the numeral 35, passes through the cored passage 36 in the plug valve 13 of the double-heading cock 11, to the port 37 in the valve bushing, as shown in Fig. 11 of the drawings. From port 37 air passes from the double-heading cock to the diaphragm chamber 38 of the reset switch 14, these ele-

ments being in piped relation with each other. Air from the application control valve thus enters the chamber 38 of the reset switch and deflects the diaphragm 22, and forces the plunger 21 out, as shown in Fig. 4 of 70 the drawings. When the plunger 21 is forced out, as indicated in Figure 4, it will be seen that the circuit, formerly established between the terminals 39 and 40 is broken.

This circuit is completed through a magnet valve 41 on the application control valve Fig. 15. When this magnet valve becomes de-energized, it vents a timing reservoir 42 to atmosphere through a restricted port 43, to the small warning whistle 32, which so sounds continuously for several seconds, at the end of which a timing valve will move down by a resilient spring action; chamber 43^a is thus connected to the atmosphere through port 44 in the engineer's brake valve.

When an automatic brake application is instituted, brake pipe pressure is connected to a pneumatic circuit controlled 44^a through a port in the brake application valve 35 90 through pipe 45, such that, when the brake application valve is in the application position, brake pipe pressure will operate a contact finger 45^a in the pneumatic circuit controller 44^a and open the circuit to the acknowledging switch, such that the application control valve magnet can only be re-energized by operating the reset switch 33. We thus have the circuit through the magnet valve 41 and the circuit through the 100 pneumatic circuit controller 44^a broken.

The re-establishment of these circuits is made in the following manner:—

The circuit through the magnet valve 41 having been broken by the closing of the double-heading cock 10, which, as explained above, broke the circuit through the reset switch 14, making it impossible to establish this circuit except by opening the double-heading cock 10. When this double-heading cock is open, air from the chamber 38 is permitted to pass through port 37 and escape to the atmosphere through port 46 drilled through the body portion of the plug valve 13. After the pressure in chamber 38 is released, the spring 30 retracts the plunger 21 and the circuit through the magnet valve 41 again is established. Having established the circuit through the magnet valve 41, it is necessary to establish the circuit through the 120 pneumatic circuit controller 44^a. The engineer's brake valve is then placed in lap position to close the vent of pipe 34 to atmosphere through port 47 in the brake valve Fig. 15. Pipe 34 is yet connected to the atmosphere through pipe 48 to the timing valve. When the train stops, the engineman having lapped his brake valve descends to the ground and operates the handle 17 of the reset switch, which action energizes an ac- 130

knowledging stick relay (not shown in the drawings) in accordance with the cab signal displayed, and this reenergizes the magnet valve 41 when reset switch is returned to 5 normal position, and the final vent to the atmosphere from pipe 34 is closed as the timing valve moves up. The reset switch is provided with a helical spring 49 in order that it returns to the normal running position as 10 soon as released. The return of the reset switch to running position is thus doubly guaranteed, since the circuit to the magnet valve 41 is not closed until the double-heading cock 10 is open and both the reset 14 and 15 acknowledging switch 14^a are in their normal running positions.

Further in connection with pneumatically operated switch 14, it will be noticed that the movement of the diaphragm 22 is such 20 that the plunger 21, which is provided with an anti-friction roller 50, coacts with a detent 51, which it moves through an angle of 60 degrees; the stroke of the plunger 21 being limited by a plurality of collars 52 and 25 53, positioned on the shaft. The angle of 60 degrees being chosen as this is quite sufficient to turn the switch shaft to either make or break the circuit as illustrated.

In the design of the reset switch 14, I provide a ring 54, which is adapted to be positioned on the switch shaft 16 and securely held in place by a pin 55, shown in position in Fig. 2 of the drawings. The ring 54 is provided with a central bore or perforation 35 56 in which the shaft 16 is designed to fit. The ring 54 has the outer portion of a segment 57 removed, leaving 120 degrees between stops 58 and 59, as shown in Fig. 5 of the drawings. Coacting with the ring 54, 40 and enveloping the same, is positioned a rotatable collar 60, which is provided with an inward projecting ledge 61, the shoulders 62 and 63 of which engage the stops 58 and 57, respectively, when the collar is rotated. In 45 order that this collar may be rotated, a pendant detent 64 is provided, which is engaged by the anti-friction roller 50 positioned in the bifurcated jaw 65 of the plunger 21. The rotatable collar 60 is further provided with a flattened surface 66 on 50 which is adapted to rest an insulation block 67, while a bridging arm 68 is sandwiched between this insulation block and a similar block 69, the assembly being held together by 55 a machine screw 70, suitably insulated from each of the above parts. It will be thus observed from Figures 1, 2, 3 and 4, that the pneumatic portion merely breaks the circuit through the magnet valve, while the circuit 60 is established by a manual operation of the reset switch handle 17.

In the operation of this train stop system, 100 cycle single phase A. C. current, from a wayside power line, is imposed upon the 65 rails. This track circuit is periodically in-

terrupted at the code frequencies established dependent upon the track conditions. Since the frequency used is much above the ordinary commercial frequencies, no trouble is experienced from stray current at commercial frequencies. 70

A master relay positioned on the locomotive and housed in an equipment box thereon, is controlled by energy from the track circuit in which a code transmitter is connected across the track rails at the three cam-operated circuit controllers, the cams of which are driven through gears by a small induction motor. The motor runs at a constant predetermined speed, and through the 75 above gears operates the cams and contacts at constant speed. When a train enters the block, a track relay opens and starts the code transmitter, and the 100 cycle A. C. track current is then interrupted by means of the 80 code transmitter the prescribed number of times per minute, depending upon the conditions of the track in advance. This coded current in the rail is picked up by the receiving coils mounted on the locomotive pilot, 85 in advance of the front engine truck wheels.

The energy induced in the receiver is amplified and then passed through a master transformer to operate a master relay, which 90 selectively energizes the proper decoding relays, and through a series of contacts, controls the cab signal indications, the current for which, as well as the amplifying circuits and relays, is taken from the headlight generator, which furnishes 32 volts. 95

The cab signals are of the position-light type and are located within the cab on both the engineer's and the fireman's side of the cab, and each display four indications. An acknowledging switch, by which automatic 100 train stop brake applications may be fo- stalled, is located in the cab adjacent the engineer's seat. A reset switch, with which the electrical equipment may be reset to 105 permit the release of brakes after an automatic brake application, is located beneath the right side of the cab. A timing valve, with piped relation to a warning whistle, is located on the right side of the locomotive ahead of the cab, and a new type of brake 110 valve replaces the standard steam engine 115 brake valve.

A brake application caused by the train stop equipment, will result in about 35 lbs. 115 brake pipe pressure reduction on locomotives when using 110 lbs. brake pipe pressure, which is the usual pressure in passenger service, and about 22 lb. brake pipe pressure reduction when using 70 lb., which is the usual pressure in freight service. The 120 automatic equipment makes only a service 125 automatic brake application. The engineman retains manual control over the brake at all times, except that brakes can not be released from cab in case an automatic train stop applica- 130

tion has been caused by failure to acknowledge a change to a more restrictive signal indication.

The indication of the cab signal is continuously determined by conditions in advance of the locomotive. Any change in conditions occurring at any time in a clear block which calls for a reduction in speed, immediately operates to initiate an application of the brakes unless a change of cab indication is acknowledged by the engineer, who thereby indicates his alertness and ability to properly handle his train.

When the signals are less than braking distance apart, the "approach restricting" indication is used. In this case a line control relay is employed, through the contacts of which the circuit for the code to the track transformer is so selected as to connect to the middle cam of the transmitter, which operates at 120 interruptions per minute.

When a track circuit is cleared by a train passing out of the block, the first impulse of coded current over the rails picks up the track relay, deenergizes one of the wayside relays and stops the code transmitter, thus restoring the track circuit to the normal alternating current feed from the autotransformer positioned at a sub-station along the trackway.

Should the engineer be able to release the brakes after an automatic brake application, without bringing his train to a stop, the purpose of the system would be defeated and for this primary reason the present invention is submitted whereby engineman can not release the brakes until the train has come to a stop and the function of re-setting has been accomplished as stated above.

40 I claim:—

1. In an inductive electro-pneumatic train stop device, an electro-pneumatic switch, a reset switch, a double-heading cock, and means for locking the reset switch through the medium of the double-heading cock.

2. In an inductive electro-pneumatic train stop device, an electro-pneumatic switch, a reset switch, a double-heading cock, and means for breaking the circuit in the reset switch when the double-heading cock is closed.

3. In combination with an inductive electro-pneumatic train stop device, a brake valve, an application control valve, a brake application valve including a magnet, an electro-pneumatic circuit controller, an acknowledging switch, a double-heading cock, a reset switch, means for locking the reset

switch against rotation through the medium of the double-heading cock, and means for 60 breaking the circuit through the magnet of the application control valve by closing the double-heading cock.

4. In combination with an inductive electro-pneumatic train stop device, an engineer's brake valve, a magnet valve, an application control valve, an electro-pneumatic reset switch, a double-heading cock, a pneumatic circuit controller, and means for 65 breaking the electric circuit through the 70 magnet valve by the operation of the reset switch through the medium of the double-heading cock.

5. In an inductive system of automatic train stop, a reset switch provided with 75 means for making and breaking a plurality of circuits through the switch, a switch case, a switch shaft, manual and pneumatic means for operating the shaft, terminals positioned within the switch case, and means for pneumatically breaking the circuit between the terminals.

6. A continuous inductive electro-pneumatic train stop device, comprising, an engineer's brake valve, a brake application valve, 85 a magnet valve, an application control valve, a pneumatic circuit controller, an acknowledging switch, a reset switch, means for energizing the circuit through the magnet of the application control valve, means for 90 breaking the circuit through the magnet valve through the medium of the double-heading cock and reset switch, and means for re-establishing the circuit through the magnet valve.

7. In combination with an inductive electro-pneumatic train stop system, a reset switch, a plurality of contact points, means for bridging the points to close the circuit, 100 pneumatic means for breaking the circuit between the contact points, and means for re-establishing the circuit through the switch.

8. In an inductive electro-pneumatic train stop device, a reset switch comprising a 105 switch case, terminal blocks positioned on either side of the case, a shaft positioned between the terminals and carrying a bridging element between the terminals, means for establishing an electric circuit through the bridging element, pneumatic means for breaking said circuit, and means for holding the bridging element against vibration when the circuit is broken.

In testimony whereof I affix my signature.
PERSIFOR FRAZER SMITH, Jr.
